UNITED STATES PATENT OFFICE

154,215

DESIGN FOR A DUPLICATING MACHINE

Robert Warren Quirk, Chicago, Ill., assignor to
Ditto, Incorporated, Chicago, Ill., a corporation
of West Virginia

Application November 26, 1948, Serial No. 149,845

Term of patent 14 years

(Cl. D64—11)

To all whom it may concern:

Be it known that I, Robert Warren Quirk, a citizen of the United States, residing at Chicago, in the county of Cook and State of Illinois, have invented a new, original, and ornamental Design for a Duplicating Machine, of which the following is a specification, reference being had to the accompanying drawings, forming a part thereof, in which,

Fig. 1 is a front perspective view of a duplicating machine, showing my new design;

Fig. 2 is a plan view thereof on a somewhat larger scale;

Fig. 3 is a front elevational view thereof, and

Fig. 4 is a rear elevational view thereof.

I claim:

The ornamental design for a duplicating machine, substantially as shown.

ROBERT WARREN QUIRK.
